SEWING MACHINE FEEDING MECHANISM

Arthur N. Hale, Park Ridge, Ill., assignor to The
Singer Manufacturing Company, Elizabeth,
N. J., a corporation of New Jersey

Application July 28, 1952, Serial No. 301,271

5 Claims. (Cl. 112—210)

1

This invention relates to sewing machines and more particularly to an improved feeding mechanism for advancing the work past the stitch-forming devices.

It is the primary object of the invention to provide a feeding mechanism which is designed as a unit capable of being put together into a sub-assembly and applied to the machine in a simple and efficient manner.

A further object of the invention is to provide a feeding mechanism in which the various parts thereof can be readily assembled and maintained in operating condition on the machine to which it is applied by means of two set screws.

A still further object of the invention is to provide a feeding mechanism capable of operating at high speed for sustained periods of time with the need of only infrequent lubrication by virtue of the use of oil impregnated sintered metal bushings at the various bearing points.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

Referring to the drawings:

Fig. 1 is a vertical sectional view taken longitudinally of the frame of a sewing machine embodying the invention.

Fig. 2 is an enlarged top plan view of the lower four-motion feeding mechanism, with a portion of the feed-length adjusting means in section.

Fig. 3 is a left end elevation with the face-plate removed from the head, and the cloth-plate, drip-pan and one of the resilient mountings in section.

Fig. 4 is a vertical sectional view taken substantially along the line 4—4, Fig. 2, showing the two-part feed advance pitman together with its controlling anchor-link.

Fig. 5 is a disassembled perspective view of the feeding mechanism with the feed-advance and feed-lift eccentrics in section.

The following detailed description has to do with the construction of the machine as it relates to the presser mechanism, and for a more complete description of the entire machine reference may be had to my copending application Serial No. 226,082, filed May 12, 1951, of which this application is a division.

Referring more in detail to the drawings, the 55

2

machine illustrated has a hollow machine-frame which is preferably cast in one piece and comprises a bed 10 from one end of which rises a standard 11 of an overhanging bracket-arm 12 terminating in a head 13.

The bed is transversely formed with depending end-walls 14 and 15 providing bearing supports for the opposite end of a main- or bed-shaft indicated generally as 16. Intermediate the end-walls 14 and 15 is a depending transverse partition 17 providing a third bearing for the bed-shaft 16. Spanning the space between the end-wall 14 and the depending partition 17 is a horizontal wall 18 affording the top of a lubrication compartment 19 closed at its bottom by a removable plate 20. The lubrication compartment 19 is in communication with the hollow 21 of the standard 11, whereby the oil-laden atmosphere created in the compartment 19 may lubricate the operating connections in the bed and standard. Adjacent the right hand end of the bracket-arm 12 there is provided a partition 22 separating the hollow of the bracket-arm 12 from the hollow of the standard 11 and supporting a rear bearing (not shown) for an arm-shaft 24. A front bearing 25 for the arm-shaft 24 is mounted in a partial partition 26 formed within the bracket-arm 12 at the point where it merges into the head 13 of the machine. A sheet-metal face-plate 27 closes the head 13 against ingress of dirt and lint and confines any spent lubricant within the head. To facilitate assembly of the mechanism within the bracket-arm 12 an access opening 28 is formed in the upper end of the standard and a detachable cover-plate 29 is provided to close said access opening.

Mounted on the bed 10 is suitable cloth-plate 30 to which is secured a throat-plate 31. The entire machine is preferably yieldingly supported on four resilient cushions 32 housed at their upper ends in aperture pads 33 cast integral with the machine-bed 10. Each of the resilient cushions 32 is bored, as at 34, to receive a locating sleeve 35 brazed or otherwise secured to a sheet-metal box-like drip-pan 36. Each of the locating sleeves 35 has a wood-screw 37 projecting through it to secure the drip-pan to a conventional table structure 38. It will be appreciated that the locating sleeves 35 position the machine within the drip-pan 36 which is attached to the table-top 38, and that the machine can be readily removed from the drip-pan by simply lifting the machine and the resilient cushions 32 off the locating sleeves 35.

The main-shaft, which is journaled for rota-

tion in the bed 10, comprises a front section 39 and a relatively shorter rear section 40; the proximate ends of the sections 39 and 40 comprising an articulated crank having separable components. The front section 39 is journaled in the plan bushed bearings 41 and 42 disposed in the partitions 14 and 17, respectively, of the bed 10. The shaft section 39 is tubular, having a longitudinal bore 43 for a major portion of its length, and adjacent its front end is formed with a feed-advance eccentric 44 and a feed-lift eccentric 45.

Carried by the front end of the shaft-section 39 is a conventional form of wing-type looper 46. Brazed or otherwise secured on the reduced rear end portion of the shaft-section 39 is a counterbalanced disk-shaped crank-cheek 47 forming one component of the articulated crank; the crank-cheek being formed in its end face with a radially extending notch 48 and having its periphery 49 cut eccentrically of the axis of rotation of the shaft-section 39, thereby to provide an eccentric for actuating a thread-nipper 50.

Projecting into the radially extending notch 48 in the crank-cheek 47 is the reduced outer end of a crank-pin 51 brazed or otherwise secured in a second counterbalanced disk-like crank-cheek 52 suitably fastened on the rear shaft-section 40. As will be seen in Fig. 1, the rear shaft-section 40 is journaled in ball-bearings 53 and 54 mounted in spaced relation in a sleeve 55 adapted to be replaceably mounted in a shaft assembly aperture 56 formed in the wall 15 of the bed. Mounted on the exposed end of the rear shaft-section is a combination hand-wheel and belt-pulley 57. For assembly purposes, the aperture 56 is sized to exceed slightly the diameter of the crank-cheek 52 so that the crank-cheek 52 with its crank-pin 51, shaft 40, ball-bearings 53 and 54, sleeve 55 and hand-wheel 57 can be assembled as a unit outside the machine and inserted through the aperture 56. A set-screw 53 locks the unit in place and a conventional resilient ring-gasket 59 prevents escape of the oil in the lubrication compartment 19-21 outwardly along the surface of the aperture 56.

Cooperating with the wing-type looper 46 in the formation of single thread chain-stitches is a thread-carrying needle 60 carried in the lower end of an endwise reciprocatory needle-bar 61 journaled in bearing-bushings 62 and 63 fixed in the machine head 13. Clamped on the needle-bar 61 is a stud 64 embraced by the lower end of a needle-bar actuating link 65 which is connected at its upper end to a rock-arm 66 clamped on the arm-shaft 24. Rocking movements are imparted to the arm-shaft 24 by means of a rock-arm 67 preferably pinned or otherwise fastened on the standard end of the arm-shaft 24; the rock-arm 67 having connected to its free end the upper end of a driving link 68 embracing at its lower end the crank-pin 51 on the rotary bed-shaft 16.

The presser mechanism, which forms the subject of a divisional application Serial No. 301,272, filed July 28, 1952, in its preferred form, comprises a suitable presser-foot 69 carried on the lower end of a vertically disposed presser-bar 70 endwise slidably mounted in the head 13. Surrounding the upper portion of the presser-bar 70 is a coil-spring 71 which biases the presser-foot 69 into engagement with the work by reacting at its upper end against a cap-screw 72 adjustably threaded in the machine-head 13 and centrally bored to provide the upper bearing for the press-

er-bar. At its lower end the coil-spring 71 engages a presser-bar guiding and lifting bracket 73 clamped by set screw 74 in selected position on the presser-bar 70. As shown in Fig. 3, the bracket 73 guides or, in other words, prevents the presser-bar 70 from turning in its bearings by being formed with a guide-lug 75 which rides in a guideway 76 milled in the machine head 13. Projecting rearwardly from the bracket 73 is a lifting extension 77 disposed vertically above the usual pivotally mounted hand-lifting cam-lever 78. Manual raising of the hand-lifting cam-lever 78 will cause it to engage the lifting extension 77 and thereby raise the presser-foot 69 against the action of the coil-spring 71. Lowering of the cam-lever 78 will permit the spring 71 to return the presser-foot 69 to its lowered work-engaging position.

Means is provided for raising the presser-foot 69 by knee-shift or foot-treadle. This means comprises a lifting rock-arm 79 secured, as by brazing, to one end of a presser-lifting rock-shaft 80 located rearwardly of the bracket-arm 12 and journaled in spaced bearings (not shown) 25 provided in the bracket-arm. The free end of the lifting rock-arm 79 is offset or bent at right angles, as at 81 (Fig. 7), to extend into a vertical open-bottom slot 82 formed in the lifting extension 77. Oscillation of the lifting rock-arm 30 79 will cause its offset end 81 to contact the lifting extension 77 and thus elevate the presser-foot 69. The slot 82 is open at its bottom to permit the hand-lifting lever 78 to be manually raised to elevate the presser-foot without causing movement of the lifting-rock-arm 79. The presser-lifting rock-shaft 80 has secured on it a rearwardly extending actuating lever 83 suitably connected to a knee-shift or foot treadle not shown. A spring 84 acting between the lever 83 and the bracket-arm normally elevates the lever 83 and maintains the lifting rock-arm 79 in engagement with a stop-pin 85 (Fig. 3).

To provide for advancing the work past the stitching devices, the present machine is equipped with a lower four-motion feeding mechanism preferably designed as a unit and capable of being put together as a sub-assembly and applied to the machine in a simple and efficient manner. To that end, the present feeding mechanism includes a feed-dog 86 clamped by a screw 87 for limited vertical adjustment on a feed-bar 88 carrying at its widened rear end a pivot rod 89 of which the opposite ends are journaled in the upstanding limbs 90 of a feed-rocker 91. The feed-rocker 91 is journaled for oscillatory movements on a fulcrum-stud 92 fixed by a set screw 93 in the machine bed 10.

Lifting movements are imparted to the feed-dog 86 by the feed-lift eccentric 45 preferably integral with the exposed end of the main- or bed-shaft 16. The feed-lift eccentric is embraced by a block 94 having flanged opposite faces engaged by the bifurcated end 95 of the feed-bar 88. Rotation of the bed-shaft 16 will impart to the feed-bar 88 and consequently the feed-dog 86, oscillatory vertical movements about the longitudinal axis of the pivot-rod 89, the oscillations being such as to raise and lower the feed-dog 86 into and out of engagement with the material through the usual feed-dog slots in the throat-plate 31.

The feed-advance and -return movements of the feed-dog 86 are derived from the feed-advance eccentric 44 also preferably formed integral with the bed-shaft 16. As will be clearly seen in Fig.

5, the feed-advance eccentric 44 is embraced by one end of a short pitman 96 connected at its opposite end to a knuckle-pin 97 of a pair of toggle-links 98 and 99. The upper end of the toggle-link 98 is connected to a pin 100 fixed in the feed-bar 88 near its rear end. The lower end of the toggle-link 99 is freely journaled on a set pivot or fulcrum-pin 101 fixed in the lower end of an anchor-arm 102 supported at its upper end on a rod 103 journaled in alined bearing holes provided in the end-wall 15 and the partition 17, the rod 103 providing a fixed pivot about which the anchor-arm 102 is manually turned. From the above description, it will be understood that rotation of the feed-advance eccentric will result in a substantially endwise movement of the upper end of the toggle-link 98; this movement of the toggle-link being transmitted by the pin 100 to the feed-bar 88. Proper relative timing between the feed-lift eccentric 45 and the feed-advance eccentric 44 effects a four-motion travel of the feed-dog 86.

It will be appreciated that the knuckle joint of the toggle-links 98 and 99 is constrained to move in an arc struck about the axis of the fulcrum-pin 101, and that by manually swinging the fulcrum-pin 101 about the axis of the anchor-arm supporting rod 103 the horizontal component of the resultant motion of knuckle-pin 97 can be changed. This results in a change in the stitch-length. To effect a shift in the position of the fulcrum-pin 101, means is provided beneath the cloth-plate 30 which can be operated in a manner such that its position of adjustment can be seen through a cut-out 104 (Fig. 3) in the cloth-plate. This means comprises a thin sheet-metal link 105 (Fig. 5) apertured, as at 106, to embrace the slightly extended end or projection 107 of the fulcrum-pin 101. At its front end the sheet-metal link 105 is apertured, as at 107', to receive a cylindrical lug 108 extending outwardly from the end-face of a thumb-disk 109 which is supported for turning movement on a stud 110 threaded into the end-wall 15. To facilitate the manual turning of the thumb-disk 109 its periphery is flanged and knurled, as at 111. Suitable numerals scribed on the periphery of the thumb-disk 109 aid in adjusting the feed to the desired stitch-length. To provide for locking the thumb-disk 109 in selected position, the stud 50 110 is fitted with a hand-lever 112 by which the stud can be conveniently tightened to clamp the thumb-disk 109 against accidental turning it being understood that the portion of the stud 110 on which the thumb-disk 109 turns is slightly shorter than the thickness of the thumb-disk 109 so that tightening of the stud by the hand-lever 112 will effectively lock the thumb-disk against the machine-bed end-wall 15. The hand-lever 112 is adjustably fastened to the stud 110 by a cap-screw 113 which secures the hand-lever against the serrated end-face 114 of the stud 110. This permits adjustment of the hand-lever 112 relative to the stud 110. It will be observed in Figs. 1 and 2 that the feeding mechanism in its entirety is located outside the lubrication compartment 19 and, in order to minimize the need for repeated hand oiling of the bearings in the feeding mechanism, bushings 115 (Fig. 5) preferably comprising oil impregnated sintered metal are used wherever possible. Also, the bearing block 94 is preferably made of the same material as the bushings.

Contributing to the simplification of the feeding mechanism is the manner in which the stitch- 75

length adjusting link 105 is maintained operatively connected to the extended end 107 of the fulcrum pin 101 and the projection 108 on the thumb-disk 109. As will be seen in Figs. 2 and 5, the thumb-disk is provided with a hub 116 and the anchor-arm 102 is milled to provide a finished face 117, the depth of the face 117 and the thickness of the hub 116 being slightly greater than the thickness of the link 105. When assembled in the machine, the stitch-length adjusting link 105 is confined at one end between the thumb-disk 109 and the machined outer face 118 of the machine-bed end-wall 15, and at its other end between the anchor-arm 102 and the outer face 118 of the machine-bed end-wall 15. Thus, it will be understood that the means for assembling the thumb-disk 109 and the anchor-arm 102 to the machine-bed also functions to retain the stitch-length adjusting link in its proper operative position. It will be appreciated also that the entire feeding mechanism is adapted to be attached to the machine by the fulcrum-stud 92. This permits the feeding mechanism to be manufactured as a unit or sub-assembly and then readily added to the machine during the final assembly thereof.

Having thus set forth the nature of the invention, what I claim herein is:

1. A sewing machine having a frame including a bed, an actuating shaft journaled in said bed, feed-advance and feed-lift eccentrics mounted on said shaft, a feed-rocker pivotally supported at one side of said actuating shaft, a feed-bar connected at one end to said feed-rocker and at its other end to said feed-lift eccentric, a feed-dog carried by said feed-bar, a pair of interconnected toggle-links of which one is connected at its extremity to said feed-bar between said feed-lift eccentric and said feed-rocker, an anchor-arm swingable about a fixed pivot and providing at its extremity a set pivot on which the extremity of the second of said toggle links is journaled, a pitman connected at one end to said feed-advance eccentric and at its other end to the knuckle joint of said toggle-links, and means for adjusting the anchor-arm about its fixed pivot thereby to shift the set pivot and regulate the feed-advance stroke imparted to said feed-dog.

2. A sewing machine having a frame including a bed, an actuating shaft journaled in said bed, feed-advance and feed-lift eccentrics mounted on said shaft, a feed-rocker pivotally supported at one side of said actuating shaft, a feed-bar connected at one end to said feed-rocker and at its other end to said feed-lift eccentric, a feed-dog carried by said feed-bar, a pair of interconnected toggle-links located at the same side of said actuating shaft as is said feed-rocker and having one of its links connected at its extremity to said feed-bar between said feed-lift eccentric and said feed-rocker, an anchor-arm swingable about a fixed pivot and providing at its extremity a set pivot on which the extremity of the second of said toggle links is journaled, a pitman connected at one end to said feed-advance eccentric and at its other end to the knuckle joint of said toggle-links, a manually controlled stitch-length regulating member mounted on said bed and located on the side of said actuating shaft remote from said feed-rocker, and operative connections between said stitch-length regulating member and anchor-arm.

3. A sewing machine having a frame includ-

ing a bed provided with a flat surface, an actuating shaft journaled in said bed, feed-advance and feed-lift eccentrics mounted on said shaft, a feed-bar, a feed-dog carried thereby, feed-lift means operatively connecting said feed-bar to said feed-lift eccentric, feed-advance and -return means connecting said feed-advance eccentric to said feed-bar, and manually controlled means for regulating the length of stitch including a shiftable anchor-arm disposed adjacent to and swingable about an axis normal to said flat surface, a projection extending from said anchor-arm toward said flat surface, a movable thumb piece, and a link connecting said thumb-piece to said projection on said shiftable anchor-arm, said link being disposed between said anchor-arm and said flat surface and being of slightly less thickness than the distance said anchor-arm is spaced from said flat surface whereby said link is retained on said projection.

4. A sewing machine having a frame including a bed provided with a flat surface, an actuating shaft journaled in said bed, feed-advance and feed-lift eccentrics mounted on said shaft, a feed-bar, a feed-dog carried thereby, feed-lift means operatively connecting said feed-bar to said feed-lift eccentric, feed-advance and -return means connecting said feed-advance eccentric to said feed-bar, and manually controlled means for regulating the length of feed-advance movement including a shiftable anchor-arm disposed adjacent to and swingable about an axis normal to said flat surface, a projection extending from said anchor-arm toward said

flat surface, a thumb-piece freely journaled on said bed and having a face disposed adjacent to said flat surface, a lug projecting from the face of said thumb-piece toward said flat surface, and a flat link connection between the projection on said anchor-arm and the lug on said thumb-piece, said flat link having a thickness less than the distance said thumb-piece is spaced from said flat surface whereby said link is retained in its normal operating position on said lug and projection.

5. A feeding mechanism for a sewing machine having a frame including a bed provided with a flat surface, comprising, a feed-dog, a feed-bar carrying said feed-dog, feed-lift and feed-advance and -return mechanisms operatively connected to said feed-bar, said feed-advance and -return mechanism including a pair of interconnected toggle links, a pivotally supported anchor-arm operatively connected to said toggle links and adjustable for effecting a change in the feed-advance stroke imparted to said feed-dog, and manually controlled means for adjusting said anchor-arm including a disk journaled on said bed and having a knurled periphery, means connecting said disk to said anchor-arm, and a locking device for preventing accidental turning of said disk.

ARTHUR N. HALE.
